UNITED STATES PATENT OFFICE

HENRY TROST, OF UNION CITY, NEW JERSEY

GAME

Application filed November 27, 1931. Serial No. 577,511.

This invention relates to a game played with cards or blocks and a game board if desired on which the cards or blocks are placed, and for the purpose of description, the game 5 will be called "Math-ez". The object of the invention is to provide a game which may be played by two or more persons, and in which a predetermined number of cards or blocks are employed and played upon a table or 10 game board in accordance with the methods of play hereinafter set forth so as to amuse and entertain both young and old as well as being educational, and to be so attractive as to maintain long interest in the game; a further 15 object being to provide a game of the class described which is simple and economical in construction and which is constructed as hereinafter described and claimed.

The invention is fully disclosed in the following specification, of which the accompanying drawing forms a part, in which the separate parts of my improvement are designated by suitable reference character in each of the views, and in which:

25 Fig. 1 is a plan view of the gameboard made according to my invention.

Fig. 2 is a view representing the several cards or blocks employed in playing the game, certain of the cards or blocks being extended to represent a number of the different 30 values or characters thereon; and,

Fig. 3 is a plan view of the blocks or cards of a modified form of game pieces.

For the purpose of illustrating one form 35 of the invention, I have shown in Fig. 1 of the drawing a gameboard *a* divided by horizontal lines *b* and vertical lines *c* into seven horizontal rows and seven vertical rows of game sections, bearing in the construction 40 shown, the numerals 1 to 49 inclusive, the first section at the upper left hand corner of the gameboard being numbered 1, and the numbers continuing consecutively in the horizontal rows, the first row ending with 45 the number 7, the next row beginning with the number 8 and ending with the number 14, etc., throughout the gameboard. The sections having the numerals 5, 10, 15, 20, 25, 30, 35, 40, 45 and 49 include other marks, 50 such for example as the double circular lines

d to designate these sections as honor sections, the feature of which will be later set forth.

I also provide a plurality of game pieces *e* which may be formed of blocks or cards, upon one face of which is arranged the numerals 55 1 to 49 inclusive. The blocks or cards having the numerals 5, 10, 15, 20, 25, 30, 35, 40, 45 and 49 are also characterized by two circles enclosing said numerals as indicated at *f* on the cards 5 and 49 shown in Fig. 2. Included with the game pieces is a block or card 60 *e*2 designated by the word "cheater" as indicated at *f*2. The block or card *e*2 constitutes a wild card, which may be played upon any one of the sections of the gameboard as later 65 set forth.

In Fig. 3 of the drawing, I have shown at *g* one game piece in the form of a block or card of a complete series of game pieces characterized the same as the game pieces indicated in Fig. 2 of the drawing, and including another symbol or character such as indicated at *h*, which may be the representation of a pig. At this time, it will be understood that each block or card in the complete series 70 of game pieces may have a different symbol or character such as the character *h* or each horizontal or vertical row may have symbols or marks of the same character other than the numerals and the word "cheater" applied 75 thereto.

At this time, it will also be understood that my invention is not limited to the specific arrangement of the gameboard herein shown and described, nor to the number of game 80 pieces employed, and the same results may be accomplished by an increased or decreased number of game pieces and the corresponding increase and decrease in the arrangement 85 of the sections on the gameboard, the distinctive characteristics of my invention residing in the manner of playing the game pieces on a table or a gameboard regardless of the 90 number of game pieces employed and the corresponding number of sections. It will also be understood that more than one cheater card may be employed in a complete series of game pieces, and this is especially important when more than two or three 95 players are engaged in playing the game, and 100

when the number of game pieces are increased.

The method of playing the game which constitutes one of the principal features of my invention resides in the fact that after one card is played by a player, it being understood that the rules governing the play of the first card may be varied from that later described, the next player in turn must play a card or block in a section bordering the section occupied by the first card played. For example, if the card 10 were the first card played, the next player must play one of the cards 3, 9, 11, 17, or the play will continue to the player who is able to play one of the cards 3, 9, 11 or 17. The sections 2, 4, 16 and 18 are not regarded as bordering the section 10; and the remainder of the play in the game continues along this fundamental rule.

To illustrate one set of fundamental rules in playing a game, which as above stated may be varied, I submit the following. If cards are employed, the same are shuffled in the usual manner of other card games, and five cards are dealt to each player, one at a time in a clockwise direction with respect to the dealer. If blocks are employed, they are all turned face downward upon the table and shuffled, and five blocks are drawn by each player. The remaining cards are placed in a stack or pile on a table adjacent the gameboard, or the blocks are left face downward so that they may be drawn one at a time.

After the cards have been dealt out, the player having the card of lowest value plays first. That is to say, if one of the players has card number 1, this card is played upon the section of the gameboard bearing the numeral 1, and the next player to the left has the next turn. This player must have card number 2 or card number 8 in order to play. If he does not have either of these cards in his hand, he draws one card from the pile. If this card drawn is a 2 or 8, he plays the same in the section of like value. If he does not draw one of these cards, the play is passed to the next player in turn, etc., each player drawing one card and then passing until one of the players plays one of the cards 2 or 8. Let us say, for example, that card 2 is played. The next player must then have card number 3, 8 or 9 in order to play, and the play continues until one of these cards has been played. At all times, one card is drawn by each player who is unable to play. Let us say, for example, that the next card played is the card 9. The next player has the option of playing cards 3, 8, 10 or 16, and the game will continue until one of the players has played all of the cards from his hand. To give another illustration, let us say that the lowest card held by any of the players playing the game, in the five cards dealt to them, is the card 11 and this is the

first card played. The next player to the left of the player playing the card 11, has the option of playing cards 4, 10, 12 or 18, the four sections which border section 11 on the gameboard. Should the second card played in the manner above set out, be the card 18, then the next player has the option of playing 4, 10, 12, 17, 19 or 25.

One method of scoring the game will be as follows. The player playing the card on any one of the sections 5, 10, 15, 20, 25, 30, 35, 40, 45 and 49 obtains in points the value designated by the section played, with the exception of the section 49 which has a point value of 50, in order to keep the score in multiples of five and to avoid uneven numbers. By this I mean, that a player playing for example card 25, obtains twenty five points, etc. Other points are scored by the completion of any horizontal or vertical row. For example, suppose all of the cards 8, 9, 10, 12, 13 and 14 have been played, and the next player plays the card 11, he will receive ten points for completing the horizontal row beginning with the character 8. At the same time, should the card 11 complete the vertical row headed by the numeral 4, he would receive ten additional points, or if the card 11 merely completed the vertical row and not the horizontal row, he would only receive ten points. The player playing the last of his cards first, will receive five points for each card held by his opponent or opponents.

The play of the cheater card or cards if two or more of them are employed in the series of game pieces, is for the purpose of a player stopping an opponent or opponents from collecting honor values or points, especially of the higher denominations, and this card is played preferably near the end of the game, or when only a few cards are held by the players.

To give an example of this play, let us assume that card 48 has been played by one of the players, and the next player holds the cheater or one of the cheaters and is of the opinion that one of his opponents has card 49. It would then be advisable to place the cheater on the section 49 of the gameboard which prevents the opponent from collecting the 50 point value, and at the same time, he will stop the player holding the card 49 from winning the game. The importance of holding the cheater for a late play in the game is due to the fact that several cards may still remain in the stack upon the table, and the party having played the cheater too early in the game, may ultimately draw the card corresponding to the space where the cheater was played, and thus automatically stop himself from winning the game and from collecting the highest score that can be made in one play.

After completing one game, the cards are all removed from the gameboard and shuffled and redealt for another game, and the play continues game after game, the 5 score being kept until it is decided to discontinue play, or if desired, a certain number of points such as a thousand may constitute the completion of a series of games, and another series may be played to determine another 10 winner.

The inclusion of the additional markings as indicated at *h* in Fig. 3 of the drawing to the cards, and to the gameboard as well, will bring other interest to the game, especially 15 for small children so that the game will become educational as well as entertaining. These characters may be arranged in such manner as to have different kinds of animals appear in the horizontal and vertical rows, 20 or symbols or marks of any other kind and class, such for example, as different colors. It will also be apparent that other honor values may be incorporated both on the gameboard and game pieces and in no way 25 do I restrict myself to the many possible deviations in the method of characterizing the board and cards and the computation of the honor scores or counts.

In playing the game, the object of each 30 player will be to so play the cards held in a hand as to prevent the other player from playing, and compel his opponent or opponents to draw other cards from the stack on the table, and at the same time to collect 35 as many of the honor values as possible. All players have the object of obtaining the highest values appearing on the board and to play the cards so as to lead up to the sections bordering the high honor sections of 40 the gameboard. With careful study and after experience in the playing of the game, it will be found that the same is very scientific and of constant interest, in that the game never starts at the same position on the 45 gameboard, nor is the progress of playing, the same, regardless of the point of starting.

In this connection, from the section 1 of the game board, the progress of the game may be downward along the section 8, 15, etc. 50 or may be horizontal along the sections 1, 2 and 3; and while moving horizontally or vertically, the game may suddenly change its course and move downwardly or upwardly on the board, as will be apparent.

55 My game may also be played without the use of a gameboard by simply providing a mathematical rule which will govern the playing of the cards on a table or other support. The rule will be that the cards are 60 played bordering the first and successive cards played by placing a card to the left of the card played, having a value one less than the value of the played card, and by placing a card to the right of one greater 65 value than the played card; whereas the card

placed above the first card played will be, in the illustration given, seven points less than said first card, and the card placed below will be seven points greater. For example, if the first card played be the card 9, 70 the card played to the left of this card must be 8, and to the right of the card 9, the card 10 must be played, the card above, 2, and the card below, 16. In like manner, all successive cards played will have increased or 75 decreased values on the basis of one and seven. As a further example, let us suppose the card 16 was placed below the card 9. The cards 15 and 17 must border 16 on the left and right respectively, and the card 23 80 will be placed beneath 16.

In this method of playing the game, there will be times when one card may have two different possible plays on the table, and it will be at the option of the player to play 85 the card in any desired position. The cheater card or cards will be played as in the other game. It will also be apparent that a rule may be given which will compel the players to play the cards to the right of the cards 90 bearing the values 1, 8, 15, 22, 29, 36 and 43 and to the left of the cards bearing the values 7, 14, 21, 28, 35, 42 and 49 so that the resulting arrangement of the cards on the 95 table will be similar to that of the arrangement of the gameboard shown in Fig. 1 assuming that forty-nine cards are used and seven is the value of the added or subtracted figure.

It will also be apparent that by employing 100 a greater or less number of playing cards or game pieces, the value of the added or subtracted figure may be increased or decreased. For example, a series of five may be employed, wherein five points are subtracted in 105 placing a card above a previously played card and five points added in placing a card therebelow. It will thus be apparent that my game is not restricted to any square arrangement of the game pieces with respect to 110 each other, and in fact that this would also be true of the gameboard if one is employed, as the arrangement of the numbered sections may be of any desired design on the gameboard.

115 It will also be understood that with a given number of cards or blocks in a game, it is not absolutely essential to use a number for addition and subtraction in a series consistent with the number of cards employed, such 120 for example as the numeral 7 above illustrated, as any other number may be used, and these numbers may be changed from time to time so as to constantly vary the mathematical equation, thus increasing the value of the 125 game and helping the player to compute the additions and subtractions of a given number with respect to other numbers and series of numbers making up a given game. If desired, these series may be worked in hun- 130

dreds, or further, the lowest card value may be 50 and terminate at 100 or 150, etc.

It will also be understood that the game may be played with chips or counters of various kinds and classes instead of keeping a score on a score pad, and as previously stated, the game may be played with any desired number of sections on the gameboard and with any desired number of cards or blocks, and in like manner, with one or more so-called cheater cards or blocks which may be otherwise termed jokers or stop cards. Various other changes in and modifications of the game herein shown and described as well as in the method of playing the same may be made within the scope of the appended claims without departing from the spirit of my invention or sacrificing its advantages.

Having fully described my invention, what I claim as new and desire to secure by Letters Patent, is:

1. A game of the class described comprising a game board having a plurality of sections thereon said sections being numbered in series to distinguish the sections one from the other, an equal number of game pieces having a corresponding series of numbers adapted to be consecutively placed on the game board on sections bordering a section or a number of sections on which game pieces have previously been played, and an additional game piece characterized in a manner contrasting to the numerals of the other game pieces to distinguish the same therefrom.

2. A game of the class described comprising a game board having a plurality of sections thereon, said sections being numbered in series to distinguish the sections one from the other, an equal number of game pieces having a corresponding series of numbers adapted to be consecutively placed on the game board on sections bordering a section or a number of sections on which game pieces have previously been played, an additional game piece characterized in a manner contrasting to the numerals of the other game pieces to distinguish the same therefrom, and means for characterizing the numerals of predetermined game pieces to give honor value thereto as said game pieces are played.

3. In a game employing a game board having forty-nine adjacent sections on which are arranged the numerals 1 to 49 inclusive, forty-nine game pieces upon which are arranged separately the numerals 1 to 49 inclusive, and a cheater game piece in addition to said first-named game pieces adapted to be played on one of the sections of said game board and having a distinguishing value.

4. In a game employing a game board having forty-nine adjacent sections on which are arranged the numerals 1 to 49 inclusive, forty-nine game pieces upon which are arranged separately the numerals 1 to 49 inclu-

sive, a cheater game piece in addition to said first-named game pieces adapted to be played on one of the sections of said game board and having a distinguishing value, and means on predetermined game pieces to distinguish the same from other game pieces and to give predetermined honor values thereto.

In testimony that I claim the foregoing as my invention I have signed my name this 25th day of November 1931.
